UNITED STATES PATENT OFFICE.

WALTER DARGUE, OF HALIFAX, ENGLAND.

SPINDLE APPARATUS FOR CAP SPINNING AND LIKE FRAMES.

Application filed April 16, 1923. Serial No. 632,408.

To all whom it may concern:

Be it known that I, WALTER DARGUE, a subject of King George V of Great Britain, residing at Halifax, in the county of York, 5 England, have invented a new and useful Improvement in Spindle Apparatus for Cap Spinning and like Frames, of which the following is a specification.

My invention relates to cap spinning and 10 like frames in which a driven bobbin is moved vertically upon a dead spindle.

The object of the invention is to provide an improved spindle apparatus for a frame of this type, which will overcome certain 15 objections appertaining to the present constructions and which provide a regulated and automatic supply of lubricant to the parts which require it.

The invention will be fully described with 20 the aid of the accompanying drawings in which—

Fig. 1 is a front view of one form of spindle apparatus embodying the invention, two spindles being shown in section and 25 elevation respectively with the lifter plate at the bottom of its traverse.

Fig. 2 is a side elevation of a spindle, the lifter plate being in this instance shown at the top of its traverse.

According to my invention in the embodiment illustrated at Figs 1 and 2, a fixed rail *a* has bushings such as *b* to receive and support bearings such as *c* in which stems *d*' on the undersides of wharles *d* are rotatable.

The bearings *c* may conveniently be secured by providing them with shoulders such as *c*' to abut against the lower ends of the bushings *b*, the upper ends of the 40 bearings being screwed as shewn to receive internally screwed rings or collars *e* resting on the rail *a*.

The lower ends of the bearings *c* receive and form supports for the enlarged screwed 45 ends of the fixed spindles *f*, and, preferably, a longitudinal fixed rail *g* is provided to anchor the lower ends of the spindles and hold them accurately in position. The upper ends of the spindles carry caps *f*' as usual.

A vertically movable lifter plate *g*', operated by any of the known mechanisms for the purpose, is disposed above the fixed rail *a* and supports bobbin hubs or driving col-

lars *h* having the usual driving projections 55 *h*', to register in recesses in the bottom ends of the bobbins *i*.

Tubes or sleeves *j* extend upwardly from the collars *h* to receive the bobbins, and downwardly from said collars through openings in the lifter plate *g*' and through the stationary wharles. The tubes *j* surround and are slidable upon the dead spindles *f* as will be understood.

The downwardly extending portions of 65 the tubes *j* have diametrically opposed longitudinal recesses or slots *j*', *j* in which inwardly projecting tongues or keys *l* carried by the wharles *d* engage, so that the said tubes are driven but can move vertically with the lifter plate.

The wharles *d* are prevented from rising in their bearings by keeper plates secured to the rail *a* and engaging collars on said wharles. One plate may conveniently serve 75 to hold down two adjacent wharles as indicated at *m* in Fig. 1.

The stems *d*' of the wharles are of ample length to form adequate supporting guides for the downwardly extending portions of 80 the tubes *j* and the lower ends of said stems may rest upon and be supported by anti-friction rings or washers at the bottom ends of the recesses or chambers in the bearings in which said stems rotate. The upper ends 85 of the bearings and the screwed holding rings *e* may be dished to form oil wells for the reception of lubricant.

The bobbin hubs or driving collars *h* preferably rest upon antifriction collars *n*, and 90 said hubs may be held down by keeper plates in the same manner as the wharles *d*.

The bearings *c* are preferably formed with chambers as shewn at *b* having communication with respective external oil cups 95 *b*', so that the lower ends of the tubes *j*, as the lifter plate descends, will dip into said lubricant and carry same up into the bearings *c* and wharles *d*. The inner surfaces of the tubes *j* are provided with helical 100 grooves *j*' which carry up lubricant from chamber *b*' and deliver it through holes *h*' at a point above the lifter plate, thus lubricating automatically the washers *n*.

The rails *a* and *g* may be combined or 105 united by a vertical web suitably pierced to give access to the oil cups *b*'.

The length of the tube *j* extending through

- the wharle obviously requires to be such that, when the lifter plate is in its highest position, the driving engagement between the tube and the wharle will be maintained.
- 5 Instead of connecting the tubes j to the wharles by keys, any other approved construction may be used which will constrain the tubes to revolve with the wharles and permit the tubes to slide vertically.
- 10 It may be that the supply of lubricant conveyed upwardly from a well b^3 by the action of the helical grooves j^2 in the inner wall of a tube, may be in excess of the quantity required for efficient lubrication.
- 15 To obviate this I may provide on the spindle, beneath the lower end of the tube, a freely slideable washer o , making a good fit with the spindle and supported by a light spiral spring p encircling the spindle, and 20 confined between said washer and the usual enlargement f^2 at the base of the spindle. The position in which the washer o is normally held by its spring, is such that as the tube descends its lower end contacts with 25 the washer before the tube reaches its lowest position. The entrances to the helical grooves j^2 are sealed or substantially sealed by such contact and are kept sealed during the remainder of the descent of the tube and 30 until, as the tube ascends again, the spring p has returned the washer back to normal position. By suitably determining the normal position of the washer o in relation to the depth of lubricant in the well, the quantity 35 of lubricant carried up at each descent of the tube can be regulated as desired.
- Having thus described my invention I wish it to be understood that the details of construction and arrangement of the parts 40 employed may be varied, and that I do not desire to be limited otherwise than by the scope of the appended claims, and what I claim is:—
1. In a spinning apparatus, a stationary bearing, a driving wharl having a non-slidable tubular stem journaled in the said bearing, a non-slidable spindle secured concentric with the said tubular stem, a tube slidable vertically on the said spindle and in 45 the said tubular stem, means for revolving
- the said tube from the wharl, and a bobbin operatively connected with the said tube.
2. A spinning apparatus as set forth in claim 1, the said tube being splined to the tubular stem of the wharl to permit it to be 55 revolved and to be slid vertically.
3. In combination with a spinning apparatus as set forth in claim 1, a reservoir for lubricant formed in the lower part of the stationary bearing and into which the lower 60 end portion of the said tube is dipped at each downstroke.
4. In combination with a spinning apparatus as set forth in claim 1, a reservoir for lubricant formed in the lower part of the 65 stationary bearing and into which the lower part of the said tube is dipped at each downstroke, said tube having an internal helical groove which raises the lubricant as the tube is revolved.
5. In combination with a spinning apparatus as set forth in claim 1, a reservoir for lubricant formed in the lower part of the stationary bearing and into which the lower 70 part of the said tube is dipped at each downstroke, said tube having an internal helical groove which raises the lubricant as the tube is revolved, and a spring-supported washer mounted in the said reservoir and operating to close the lower end of the said helical 75 groove at a predetermined point of the downstroke of the tube.
6. A spinning apparatus as set forth in claim 1, the means for connecting the bobbin to the said tube comprising a driving collar 80 secured on the tube, the said collar and bobbin having interlocking parts so that they revolve together, and said bobbin being removable from the tube.
7. A spinning apparatus as set forth in 85 claim 1, the said non-slidable spindle being provided at its lower part with a screw-threaded portion of larger diameter than its main portion, said screwthreaded portion being screwed into the lower part of the said stationary bearing and securing the said spindle to it.
- In testimony whereof I affix my signature.
- WALTER DARGUE.
